DESIGN FOR A BROOCH OR SIMILAR ARTICLE

Lester Gaba, New York, N. Y., assignor to Albert
Weiner, Providence, R. I., doing business as
Albert Manufacturing Company

Application February 15, 1938, Serial No. 75,144

Term of patent 3½ years

To all whom it may concern:

Be it known that I, Lester Gaba, a citizen of the United States and a resident of New York, in the county of New York and State of New York, have invented a new, original, and ornamental Design for a Brooch or Similar Article, of which the following is a specification, reference being had to the accompanying drawing, forming part thereof, and in which

Fig. 1 is a front view of a brooch or similar article showing my new design, and

Fig. 2 is an edge view thereof.

The distinctive feature of the design consists of a lower, upwardly turned border of elongated, beveled stones arranged horizontally, a middle, downwardly curved band of elongated stones arranged horizontally and a top band of vertical stones arranged side by side.

I claim:

The ornamental design for a brooch or similar article substantially as shown and described.

LESTER GABA.
